US00D873602S

(12) **United States Design Patent** (10) Patent No.: **US D873,602 S**
Varjabedian et al. (45) Date of Patent: ** Jan. 28, 2020

(54) **LID PART OF A FOOD PREPARATION DEVICE**

(71) Applicant: **SHARKNINJA OPERATING LLC**, Needham, MA (US)

(72) Inventors: **Nicholas Varjabedian**, Middleboro, MA (US); **Benjamin Lenart**, Malden, MA (US)

(73) Assignee: **SHARKNINJA OPERATING LLC**, Needham, MA (US)

(**) Term: **15 Years**

(21) Appl. No.: **29/679,917**

(22) Filed: **Feb. 11, 2019**

Related U.S. Application Data

(63) Continuation of application No. 29/659,571, filed on Aug. 9, 2018.

(57) **CLAIM**

The ornamental design for a lid part of a food preparation device, as shown and described.

DESCRIPTION

FIG. 1 is a perspective view of a lid part of food preparation device, showing our new design thereof;

FIG. 2 is a front view of the embodiment shown in FIG. 1;

FIG. 3 is a rear view of the embodiment shown in FIG. 1;

FIG. 4 is side view of the embodiment shown in FIG. 1;

FIG. 5 is another side view of the embodiment shown in FIG. 1;

FIG. 6 is a top view of the embodiment shown in FIG. 1; and,

FIG. 7 is a bottom view of the embodiment shown in FIG. 1.

The broken lines in the figures are for environmental purposes only and form no part of the claimed design.
